UNITED STATES PATENT OFFICE

JOHN WILDER, OF NILES, OHIO, ASSIGNOR TO WILDER METAL COMPANY, OF NILES, OHIO, A CORPORATION OF DELAWARE

PROCESS AND APPARATUS FOR COATING FERRIC ARTICLES WITH A METALLIC PROTECTIVE

Application filed June 28, 1930. Serial No. 464,681.

This invention relates generally to the process of coating or plating steel or iron sheets with a covering film or surface of an alloy of other metals, and to mechanism for practising such process.

In particular, this invention relates to the process wherein the coating or plating compound is an alloy, such as is set forth in the United States Patent of John Wilder, No. 10 942,803, dated December 7, 1909.

The principal objects of the invention are:

First, the provision of means whereby the steel or iron plate may be subjected to the action of a water bath immediately after its 15 immersion in the molten coating compound, whereby a high luster to the finished product will be insured and a dull or murky appearance prevented.

Second, the provision of means whereby the 20 time elapsing between the emerging of the plate under treatment from its coating bath and its immersion in the immediately following water bath may be very closely and accurately regulated in order that best results

25 may be obtained. It has been determined that these results are best obtained when the plate is subjected to the action of the water bath just before crystallization of the coating compound upon its surface sets in. As the 30 time required for this crystallizing to start is very short and its duration is dependent upon numerous factors, such, for example, as the nature of the coating compound, its temperature, the length of time the plate under treatment 35 is subjected to its action, the character, size and thickness of the plate, atmospheric conditions, etc., it will be readily understood that control of the time element must be very precise. Such control is provided.

40 Third, the provision of means for the specified time control in such wise that its accurate regulation may be effected easily, quickly and without interference with, or 45 stopping of, the steady progress of the plates under treatment through the provided mechanism.

Fourth, other objects and advantages, such 50 as will appear from the following detailed description of the invention and the manner

of its operation, will be particularly pointed out in the appended claims.

In the accompanying sheet of drawing, Figure 1^a is a central vertical sectional view, somewhat diagrammatic in nature, of 55 the plate receiving end of a machine constructed in accordance with and for practising the invention;

Figure 1^b is a similar view of the sectional portion of the machine and continuing the 60 showing from Figure 1^a; and,

Figure 1^c is a similar view of the plate delivery end of the machine and continuing the showing from Figure 1^b.

Briefly stated, the machine illustrated comprises, in order, a flux or acid bath, a drier, 65 a coating bath, a water bath, and another drier, together with means for feeding the plates under treatment successively therethrough and means for regulating the position of the water bath with respect to the 70 position of the coating bath.

The machine will now be described in detail.

Each steel or iron plate to be treated is, 75 after the customary preparatory pickling with diluted sulphuric acid, fed over an apron 1 between rubber rollers 2, into a flux or acid bath contained in a tank 3. From this tank the plate passes along the apron 1 between 80 rubber rollers 4 and onto an endless conveyor 5, which carries it through a drier 6 wherein a temperature preferably between 150° and 300° F. is maintained.

The endless conveyor delivers the dried 85 plate onto a table 7, from which it is removed and passed between guide plates 8, through the coating bath in a tank 9. As the plate leaves the guides 8, it passes between rollers 10, under a guide plate 11 and onto 90 an endless conveyor 12.

At this point in the description, it is to be particularly noted that it is preferred to subject the plate, while in tank 9, to the action of a molten coating compound 22, 95 such as set forth in U. S. Patent 942,803, hereinbefore mentioned. Upon the surface of the molten mass in this tank is a fluid flux 23, preferably of sal ammoniac and charcoal, and the level maintained within the tank is 100

- such that the flux 23 is about on a line with the centers of the rollers 10. These rollers will thus, at all times, remain clean and none of the plating alloy will adhere to them.
- 5 The temperature to be maintained in the coating bath in tank 9 is approximately between 850° and 1200° F., according to the nature of the compound and the degree of coating desired.
- 10 As the coated plate is delivered to the endless conveyor 12, it is carried thereby (see Figure 1^b) to a water bath contained in a tank 13, passing under a roller 14 mounted on the tank and so positioned with respect to the
- 15 level of water therein as to insure submergence of the plate. The temperature of the water in this tank is of great importance in the production of proper results. It must be at least 150° F., and may be much higher, depending upon the thickness of the plate and the amount of coating deposited thereon.
- 20 As previously pointed out, it is of the utmost importance, in order to obtain the desired results, that the time when the plate reaches the water after leaving the coating bath be under precise control. To provide for this control, the tank 13 is mounted upon wheels 15 adapted to run upon rails 16. It will readily be understood how this permits
- 25 adjustment of the tank 13 with respect to the fixed position of the tank 9, the tank 13 being easily and quickly moved closer to or further from the tank 9 without any interference with the operation in general.
- 30 As the water washed plate, still carried by the endless conveyor 12, passes from the tank 13, it is passed between rubber rollers 17 onto another endless conveyor 18, which carries it through a drier 19 (see Figures 1^b
- 35 and 1^c), wherein the temperature is such as to properly dry it of surface moisture, and delivers it at a leveling roll device 20, from which it passes, finally, to a table or truck 21.
- 40 It is, of course, to be understood that the invention is not limited to the exact construction shown and described; as it is obvious to any one skilled in the art that alternative forms of structure may readily be employed, as well as numerous changes in form,
- 45 arrangement, and proportion of parts, all without any variation from the nature of the invention, or departure from the spirit thereof, as, for example, in extremely cold weather and under such conditions when it is found
- 50 that the necessary high temperatures of the sheets before entering the water bath or tank 13 has not been maintained at such a proper temperature so that when the sheets enter said water bath 13 the metal will not have
- 55 set to such an extent that the water cooling will not have the proper effect there is provided an auxiliary heater 6^a interposed between the tank 9 and tank 13, and, preferably, similar in construction to heater or drier
- 60 6, and while such provision is illustrated and

described, it is not absolutely necessary to carry out the process but is only resorted to when the occasion, as pointed out, arises.

What is claimed is:

1. In the method of coating metallic plates, wherein the plates are subjected to the action of molten coating compound and directly thereafter to a cooling medium for the purpose of setting said compound on the plates, the step of providing a variable control of the time interval elapsing between the subjection of the plates to the coating compound and the subjection to the cooling medium. 70
2. The combination, in coating mechanism for metallic plates, of a container in which such plates are subjected to the action of a molten coating compound, a container in which they are cooled and washed, means for conveying them from said first container to said second container, and adjustable means for varying the distance between said containers for changing the time elapsed for the passing of the plates from the first to the second container. 85
3. The combination, in coating mechanism for metallic plates, of a container in which such plates are subjected to the action of a molten coating compound, a container in which they are cooled and washed, one of said containers being fixedly mounted, and the other being adjustably mounted in respect thereto, and means for conveying plates from said first container to said second container. 90
4. The combination, in coating mechanism for metallic plates, of a container in which such plates are subjected to the action of a molten coating compound, a container in which they are cooled and washed, one of said containers being fixedly mounted, and the other being provided with and supported on wheels, and adjustable in respect to said fixed container, and means for conveying the plates from said first container to said second container. 100
5. The combination, in coating mechanism for metallic plates, of a container wherein such plates are subjected to the action of a molten coating compound, a container wherein they are cooled and washed, means for conveying them from said first container to said second container, and means for adjusting the position of said second container in respect to said first container and said conveying means and without interruption of the operation of the mechanism or disturbing said conveying means. 115
6. The combination, in coating mechanism for metallic plates, of a container wherein such plates are subjected to the action of a molten coating compound, a second container wherein they are cooled and washed, a wheeled mounting therefor, tracks upon which such wheeled mounting may be moved 125
- 120
- 130

to adjust the position of the receiving end of said second container in respect to the discharge end of said first container, and means passing through said second container for conveying the plates from said first container to said second container.

7. The combination, in coating mechanism for metallic plates, of a first container in which such plates are subjected to the action of a molten coating compound, a second container in which they are cooled and washed, means for conveying them from said first container to said second container, and adjustable means for varying the distance between the discharge end of said first container and charging end of second container, and a reheater interposed between the molten coating compound container and subsequent cooling and washing container.

20 8. The combination, in coating mechanism for metallic plates, of a first container wherein such plates are subjected to the action of a molten coating compound, a second container wherein they are cooled and washed, a 25 wheeled mounting for said second container, tracks upon which such wheeled mounting may be moved to adjust the position of the inlet end of said second container in respect to the discharge end of said first container, 30 and means for conveying the plates from said first container to said second container, and a reheater interposed between the molten coating compound container and subsequent cooling and washing container.

35 In testimony whereof I hereunto affix my signature.

JOHN WILDER.
